ROLLING MILL COUPLING BOX SUPPORT

Myles Morgan and Joseph M. O'Malley, Worcester, Mass., assignors to Morgan Construction Company, Worcester, Mass., a corporation of Massachusetts

Application November 8, 1947, Serial No. 784,802

3 Claims. (Cl. 211—1)

1

This invention relates to rolling mills, and more particularly to the construction and arrangement of an apparatus which will facilitate the changing of rolls in a horizontal rolling mill.

In many rolling mills, such for example as so-called "merchant" mills, it is a common practice to provide a horizontal roll stand comprising a pair of horizontal rolls formed with a plurality of circumferential grooves and rotatably supported in a roll housing. The rolls are connected by universal coupling spindles to a pair of intermeshing horizontal mill pinions which are rotatably supported in a pinion housing, one of the pinions being driven by a suitable source of power. The rolls usually have fluted wabblers on their ends, and these wabblers fit within roll coupling boxes on the ends of the spindles. It is frequently necessary to change the rolls, which involves the withdrawal of the wabblers from the coupling boxes and the insertion of the wabblers of the newly mounted rolls in the coupling boxes. This is ordinarily a rather difficult and often dangerous task, largely because no suitable means is available to hold the coupling boxes in position during the roll-changing operation.

It is one object of the invention to provide a new and advantageous mechanism which will facilitate the changing of rolls in a horizontal rolling mill.

It is a further object of the invention to provide a simple, inexpensive and thoroughly dependable apparatus to support the universal spindles in a horizontal rolling mill during roll changes.

It is a further object of the invention to provide an apparatus which will support the roll coupling boxes of the universal spindles in a horizontal rolling mill in such a manner as to facilitate the withdrawal of the roll wabblers from these boxes, and the insertion of roll wabblers therein, during roll changes.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is an elevation of a horizontal rolling mill, with certain parts broken away for clearness of illustration;

Fig. 2 is a section taken on the line 2—2 of Fig. 1;

Fig. 3 is a section taken on the line 3—3 of Fig. 1;

2

Fig. 4 is an enlarged longitudinal section through the mill pinion housing;

Fig. 5 is a section taken on the line 5—5 of Fig. 4;

Fig. 6 is an end elevation of part of a coupling box;

Fig. 7 is a fragmentary plan view showing a spindle supporting device in use; and

Fig. 8 is a view taken as indicated by the line 10 8—8 of Fig. 7.

The embodiment illustrated comprises a foundation 10 of concrete or other suitable material which serves to support a horizontally elongated metal base 11. This base is shaped to provide an elevated platform 12 adjacent one end, and two spaced parallel horizontal rails 14 which extend from the other end of the base toward the platform. A pinion housing 15 is mounted on a fixed position on the platform 12, and the two upright housings 16 of a horizontal roll stand 17 are slidably supported on the rails 14. This roll stand comprises a pair of grooved horizontal rolls 19, with fluted wabblers 20 on the ends of the roll necks, and the usual screw-downs 21 at the tops of the housings. The housing feet are releasably clamped to the rails 14 by means of suitable bolts 23 which may be tightened by wedges 24 extending through slots in the upper portions of the bolts in known manner.

30 The roll stand 17 may be moved along the rails 14 by means of a fluid actuated motor 26 mounted on the adjacent end of the base 11 and having a reciprocable piston rod 27 which extends horizontally between the rails. On the end of this rod there is mounted a fork 28 which is connected by a pin 29 to a bracket 30 secured to the bottom of one housing 16. The motor 26 may be controlled manually by any suitable four-way valve (not shown) in a well known manner.

40 The pinion housing 15 serves to enclose two intermeshing horizontal mill pinions 32 (Figs. 4 and 5), which may be of the double helical or herringbone type. The end portions of the pinions are rotatably mounted in bearings 33 supported by the housing. Each of the pinions 32 is provided with a central longitudinal bore 34 of noncircular cross section. As best shown in Fig. 5, these bores are preferably shaped to provide a plurality of grooves or flutes 35. The lower pinion 32 is driven by a spindle 31 having a head 38 thereon shaped to fit within the outer end of the pinion bore 34. As shown in Fig. 1, this spindle 31 is connected by a coupling 39 to the shaft of an electric motor 40. A circular plate 42 is secured to the outer end of the upper

45

50

55

pinion, and an annular plate 43 is secured to the outer end of the lower pinion, in surrounding relation to the spindle 37. These plates aid in retaining lubricant within the bores and in excluding dirt therefrom.

The pinions 32 are connected to the rolls 19 to drive the same. For this purpose there is slidably mounted within each bore 34 a hollow coupling box 45 having outwardly projecting lugs 46 (Fig. 6) to engage the flutes 35, and inwardly projecting gear teeth 47 to engage the teeth of a coupling head 49 keyed to one end of a spindle 50. On the other end of the spindle there is keyed a similar toothed coupling head 51 located within a coupling box 53, this box having internal 15 gear teeth engaging the external teeth of the coupling head. Each box 53 is provided with a sleeve portion 54 which extends over the corresponding wobbler 20 and interfits in known manner with the flutes thereof. Screws 55 releasably secure the sleeves 54 to the wobblers. Each box 53 further includes an end plate 57 which projects slightly beyond the peripheral surface of the sleeve 54 to provide a shoulder. The teeth on the heads 49 and 51 are preferably made with a 20 spherical pitch surface, as fully disclosed in the patent to Myles Morgan No. 2,136,947, granted November 15, 1938. Consequently each spindle 50 is universally connected at its ends to the corresponding coupling boxes 45 and 53 so that vertical 25 adjustments of the rolls 19 may be made without interference with the roll driving mechanism. An annular seal 60 is mounted on the inner end of each pinion 32 in surrounding relation to the corresponding spindle 50, these seals aiding in the retention of lubricant and the exclusion of dirt.

In order to facilitate roll changes, provision is made whereby the coupling boxes 53 may be supported while the roll wobblers 20 are withdrawn therefrom. For this purpose a frame 62 is mounted on the platform 12 close to the front end of the pinion housing 15, i. e. the end toward the roll stand 17. This frame 62 is preferably of welded construction and comprises two pairs of uprights 63 located on opposite sides of the spindles 50. Each pair of uprights 63 is connected by two vertically spaced horizontal bars 64 with their ends welded or otherwise secured within holes in the uprights. These bars are 30 arranged to be engaged by the supporting hooks 66 of two chain-sling ratchet hoists 67 (Figs. 7 and 8) of a well known construction, each hoist having an operating handle 68. The hoists 67 are arranged to extend beneath the coupling 35 boxes 53 when the boxes are moved close to the pinion housing 15. One of the rear uprights 63 is provided with two vertically spaced guides 70 each of which supports a manually slidable latch 71 having a handle 72. These latches may be 40 moved inwardly to engage the edges of the end plates 57 of the coupling boxes and hold these boxes against axial movements as the wobblers 20 are withdrawn or inserted.

As shown in Fig. 1, a horizontal guide trough 75 may be mounted above the drive spindle 37 and close to the rear end of the pinion housing 15. This is feasible for the reason that the pinion housing is supported in a fixed position. It will be understood that the trough 75 may direct an 50 approaching hot metal bar into the usual repeater (not shown) which in turn directs the bar into the rolls 19.

The operation of the invention will now be apparent from the above disclosure. The motor 40

5 will drive the lower pinion 32 through the medium of the coupling 39 and the spindle 37, and the pinions 32 will drive the respective rolls 19 through the medium of the coupling boxes 45, the spindles 50, and the coupling boxes 53. The universal connections between the spindle heads 49 and 51 and the coupling boxes 45 and 53 respectively will accommodate the required vertical adjustments of the rolls 19. When it becomes necessary to employ a different set of roll grooves, the bolt wedges 24 will be loosened, the roll stand 17 will be moved along the rails 14 by the fluid motor 26 to the desired position, and the wedges 24 will then be tightened. During this movement of the roll stand, the coupling boxes 45 will slide axially within the pinion bores 34, and the pinion housing 15 will remain fixed in position. When the rolls have to be changed, the roll stand 17 will first be moved rearwardly far enough to permit the latches 71 to be moved inwardly into engagement with the edges of the plates 57 of the coupling boxes 53, as shown in Figs. 7 and 8. The hoists 67 will then be hung in position beneath the coupling boxes and tightened by means of the handles 68, and the screws 55 will be loosened or removed. Thereupon the roll stand will be moved forwardly again, thus withdrawing the wobblers 20 from the coupling boxes, so that the rolls may then be changed in the usual manner. To connect the new rolls to the driving mechanism this procedure will be reversed.

It will be apparent that the invention is of great assistance during roll changes, and that it reduces the danger to the operator.

Having thus described our invention, what we claim as new and desire to secure by Letters Patent is:

1. A support for the roll coupling boxes of a horizontal rolling mill, comprising a frame having two horizontally spaced upright members adapted to receive the coupling boxes between them, and two sling hoists located one above the other and extending across from one upright member to the other in the form of U-shaped loops adapted to carry the weight of the coupling boxes during roll changes in the mill.

2. A support as set forth in claim 1, in which manually operable latches are mounted on the frame and adapted to engage the coupling boxes and prevent axial movement thereof.

3. A support as set forth in claim 1, in which each sling hoist includes a manually operable handle arranged to vary the size of the loop as desired.

MYLES MORGAN.
JOSEPH M. O'MALLEY.
